ATTORNEYS

UNITED STATES PATENT OFFICE.

CHARLES PEROTTI, OF WATERBURY, CONNECTICUT, ASSIGNOR OF ONE-HALF TO
FREDERICK W. PALOMBA, OF WATERBURY, CONNECTICUT.

PENCIL.

1,404,138.

Specification of Letters Patent. Patented Jan. 17, 1922.

Application filed February 15, 1921. Serial No. 445,152.

To all whom it may concern:

Be it known that I, CHARLES PEROTTI, a citizen of the United States, residing at Waterbury, in the county of New Haven 5 and State of Connecticut, have invented certain new and useful Improvements in Pencils; and I do hereby declare the following to be a full, clear, and exact description of the invention, such as will enable others skilled in the art to which it appertains to 10 make and use the same.

This invention relates to new and useful improvements in pencils, and more particularly to a pencil of the type wherein the 15 lead is normally disposed within the casing of the pencil when not in use and can be readily positioned for use when so desired and retracted into the casing after use to thus prevent the accidental breaking of the 20 lead when carried about in the pocket. The main object of the invention is the provision of a pencil of this character having a suitable eraser attachment normally disposed within the casing of the pencil and provided 25 with means for projecting the eraser from the casing upon release of the same, the carrying member comprising a suitable receptacle whereby additional lead for use in the pencil can be carried.

30 A further object of the present invention is the provision of a pencil comprising a casing in which all of the component parts are normally disposed within the casing so that the pencil can be readily carried about 35 in the pocket or other receptacle and the lead readily positioned for use or retracted after use and wherein the eraser member can be quickly and readily brought into position for use from within the casing.

40 With the above and other objects in view the invention consists in the novel features of construction, combination and arrangement of parts hereinafter more fully set forth, pointed out in the claims and shown 45 in the accompanying drawings in which:

Figure 1 is a side elevation of a pencil constructed in accordance with my invention, the lead being shown positioned ready for use;

50 Fig. 2 is a similar view showing the eraser and lead both in position for use;

Fig. 3 is a longitudinal sectional view, parts being shown in elevation with the eraser shown in its normal position within 55 the casing;

Fig. 4 is a similar view showing the eraser

in a protracted position and the support for the eraser in cross section showing the receptacle for the additional lead; and

Fig. 5 is a side elevation of the guiding 60 member for the lead.

In carrying out my invention I provide a suitable casing generally indicated by the numeral 1, tubular in form and tapered at one end into a frustum of a cone 2 having an 65 opening communicating with the interior of the casing through which the lead 3 is extended for use or retracted into the casing when not in use.

Arranged within the casing is a tubular 70 member 4 having a substantially conical shaped end portion 5 adapted to correspond with the cone portion 2 of the casing 1 so that the member 4 will fit snugly within the cone end of the casing when placed in position as shown in Figs. 3 and 4. The interior of this member 4 is provided with screw threads from one end which extend to the cone portion 5 and mounted for threaded adjustment within this tube 4 is a sleeve 6, 80 the exterior of which is threaded and adapted for adjustment within the tubular member 4.

The sleeve member 6 is mounted for sliding movement upon the rotating tube 7, the 85 tube 7 extends into a central opening in the cone portion 5 of the tube 4 and is provided with a longitudinal slot 8 in which the pin 9 operates upon sliding movement of the sleeve 6 on the tube 7, the turning movement of the tube 7 moving the sleeve 6 longitudinally upon the tube 7. Mounted for sliding movement within the tube 7 is a sleeve 10 having yieldable opposed arcuate 90 fingers 11 formed at one end and adapted 95 for sliding movement through the conical portion 5 of the tube 4 into the cone portion 2 of the casing 1. It will be noted that the sleeve 10 is slightly tapered and the outer end of the tube 7 is also tapered at the point 100 where it enters the conical portion 5 of the tube 4 so that upon movement of the sleeve 10, through the medium of the sleeve 6, the outward movement of the sleeve 10 will be limited to the position shown in Fig. 4 or 10.

until the larger portion of the cone shape of the sleeve 10 reaches the tapered portion of the sleeve 7. Connected to the transverse pin 9 of the sleeve 6 is a push rod 12 which extends outwardly through the sleeve 10 11 and between the fingers 11 and adapted to have its outer end engage the inner end of

the lead 3 so that upon movement of the sleeve 6 toward the conical end of the casing, the rod 12 will engage the lead and push the same outwardly to the position shown in Fig. 4 and when the sleeve 10 and fingers 11 are in the position illustrated in Fig. 4, the fingers 11 will frictionally engage the lead and retain it in its proper position so that when it is desired to retract the lead within the casing, the backward movement of the sleeve 6 will tend to draw the lead inwardly by having the cross pin 9 engaging with the pin 13 extended across the inner ends of the arms 14 which are formed integral with the sleeve 10 and extended into the sleeve 7. The sleeve 10 and fingers 11 will then be drawn into the casing, carrying the lead with them. It will be noted that the rod 12 is used for projecting the lead outwardly as fast as it is worn off at the point, but the sleeve 10 and fingers 11 retract the lead into the casing when not in use.

Connected to the inner end of the tube 7 by means of the cross pin 15 is the operating sleeve 16. This sleeve 16 is securely retained in position within the casing 1 by having the sleeve provided with an annular groove 17 and mounted within this groove is a collar 18 connected to the casing 1 by means of the screw 19 so that the sleeve 16 can be readily rotated within the casing 1 and securely held against any longitudinal movement.

In order to provide means whereby the sleeve 16 can be readily rotated by the operator, I provide an enlarged head portion 20 having a sleeve 21 mounted upon the outer end of the sleeve 16 and secured thereto by means of the screw 22 so that when the head portion 20 is grasped by the fingers, the operator can readily rotate the sleeve 16 to position the lead for use or retract the same into the casing through the rotation of the sleeve 6 within the tube 4, said sleeve 6 and tube 4 being provided with corresponding screw threads whereby upon rotation of the sleeve 6 it will be moved longitudinally within the tube 4.

Further in connection with my improved pencil I have provided means whereby an eraser member can be normally carried within the casing 1 when not in use and can be readily protracted from the casing when it is desired to position the same for use. In carrying out this means I provide a cylinder 23, the inner end of which is closed and provided with an annular flange 24 adapted to fit within the sleeve 16 for sliding movement. In Fig. 3 I have shown the cylinder 23 normally disposed within the casing and the coil spring 25 which is disposed between the closed end of the cylinder 23 and the inner end of the tube 7 under compression. In order to retain the cylinder 23 in position, the cover

member 26 which is pivoted to the head 20 as at 27, is in its closed position and retained in this position by means of the spring catch 28 carried by the head 20 and engaging the catch 29 on the cover 26. The inner face 70 of the cover 26 is provided with a rubber facing 30 against which the eraser member 31 abuts to retain the cylinder 23 within the casing. The eraser member 31 is carried by a cap 32 threaded upon the outer end of the cylinder 23 so that when the eraser member 31 becomes worn down, it can be readily replaced with a new one by removing the cap 32 and putting a new eraser in the cap.

When it is desired to release the eraser member from within the casing, the catch member 28, is manipulated through the finger pin 33 which, by pressing downwardly upon the finger pin 33, will release the catch member 28 from the hook 29 so that the 85 eraser member, through the tension of the spring 25 will be forced outwardly to its position shown in Fig. 4, and in order to limit the outward sliding movement of the cylinder 23 a stop ring 34 is positioned 90 within the outer end of the sleeve 16 and secured in place by having the inner end of the screw member 22 engaging with the same.

From the above description taken in connection with the accompanying drawings, it will be readily apparent that the operation of my improved pencil is as follows. When it is desired to extend the lead 3 to a position for use, the head 20 is grasped by the 100 fingers of the operator and rotated, which in turn will impart a rotary movement to the sleeve 16, tube 7 and sleeve 6, the sleeve 6 being moved longitudinally within the tube 4 through the action of the screw threaded connection between said sleeve 6 and tube 4, the movement of the sleeve 6 carrying the sleeve 10 and rod 12 toward the conical end 2 of the casing 1. From the position illustrated in Fig. 4, it will be noted that the 110 lead 3 is protracted to a position ready for use and should the lead be used to such an extent that it will become worn down to the cone portion 2, the head 20 can be rotated to slide the sleeve 6 longitudinally, 115 which in turn will move the rod 12 outwardly and force the lead 3 to a position for further use. When it is desired to retract the lead 3 into the casing, the head 20 is rotated in a reverse direction, the sleeve 6 120 moving within the tube 4 through rotation of the tube 7 until the cross pin 9 strikes the pin 13 so that the sleeve 10 and fingers 11 which grasp the lead 3 will be moved longitudinally into the casing, carrying the 125 lead with them.

Should it be found necessary to use the eraser member 31, the finger pin 33 can be pressed to release the cover 26 and permit the eraser to be protracted from the casing 130

through the medium of the spring 25 which is normally under tension when the cylinder 23 carrying the eraser 31 is disposed within the casing. From this it will be apparent 5 that I have provided a simple and compact pencil wherein the lead and eraser member are normally carried within a suitable protecting casing and can be readily positioned for use when desired or arranged within the 10 casing when not in use.

I also wish to call attention to the fact that the cylinder 23 can be used for carrying an extra supply of lead for use in the outer end of the pencil. The pieces of lead can 15 be readily placed within the cylinder 23 or removed therefrom by removal of the cap 32.

I claim:

1. A pencil including a tubular body member, a sleeve mounted for rotation therein, 20 a tube connected with one end of the sleeve, a second tube arranged within the body and surrounding the first tube, said second tube having interior screw threads, an adjustable sleeve mounted upon the first tube and having 25 threaded engagement with the second tube, a transverse pin extending through the adjustable sleeve and the first tube whereby turning movement of the first tube will adjust the sleeve, means operated 30 by the pin through the rotation of the first tube for projecting and retracting a lead point through one end of the tubular body.

2. A device of the class described including a tubular body member having a tapering end, a tube arranged within the body and having one end tapered to project into the tapered end of the body, a second tube arranged within the first tube, an adjustable sleeve carried by the second tube and having 40 threaded engagement with the first tube, means whereby to rotate the second tube for adjusting the sleeve thereon, a transverse pin connecting the sleeve and second tube, a second sleeve arranged within the second 45 tube, having yieldable engaging fingers for gripping a lead point whereby the adjustment of the sleeve on the second tube will project and retract the lead point through the tapered end of the body.

50 3. A pencil of the class described including a tubular body member, a rotatable sleeve therein, a head portion connected to one end of the sleeve whereby to impart movement to the same, a pivoted cover member closing the outer end of the head portion, a cylinder member normally disposed within said sleeve, means for retaining the closure member in a closed position to retain the cylinder within the sleeve and a coil 55 spring disposed within the inner end of the 60

sleeve and the cylinder whereby to project the cylinder upon opening of the closure member and an eraser member detachably connected with the end of the cylinder.

4. A pencil including a tubular body 65 member, a tapering portion upon one end of said body, a sleeve mounted for adjustment within the body, yieldable fingers carried by one end of said sleeve for grasping a portion of lead, means for adjusting said sleeve longitudinally to protract or retract the lead through the tapered end of the body, a movable cylinder normally disposed within the other end of the body, an eraser member carried by the outer end of said cylinder, a 70 closure member normally closing the end of the body opposite the tapering portion to retain the cylinder within the body and a coil spring arranged within the body and bearing against the inner end of the cylinder to 75 protract the cylinder upon releasing the closure member.

5. A pencil including a tubular body member having a tapered end portion, means adjustable within the body for protracting 85 and retracting a lead point through the tapered end of the body, a sleeve mounted in the other end of said body for rotation, a pivoted closure member at the outer end of said sleeve, a cylinder normally disposed within 90 the sleeve, an eraser member carried by the outer end of the cylinder and a coil spring disposed between the inner end of the cylinder and the inner end of the sleeve, normally under tension when the cylinder is in 95 the sleeve and adapted to protract the cylinder upon release of the closure member.

6. A device of the class described including a tubular body member, a sleeve mounted for rotation therein, a pivoted closure 100 member at the outer end of said sleeve, a cylinder normally disposed within the sleeve, an eraser member carried at the outer end of the cylinder and a coil spring disposed between the inner end of the cylinder and the 105 inner end of the sleeve normally under tension when the cylinder is in the sleeve and adapted to project the cylinder upon release of the closure member.

7. A pencil including a tubular body, a 110 sleeve mounted in one end of said body, a movable cylinder normally disposed within the sleeve, a closure member for the outer end of the sleeve to retain the cylinder in its normal position and means within the sleeve 115 whereby to project the cylinder upon release of the closure member.

In testimony whereof I affix my signature.

CHARLES PERROTTI.
